Primary Examiner — George D. Kirschbaum*Assistant Examiner* — Maria J Edwards(74) *Attorney, Agent, or Firm* — Wood, Phillips, Katz, Clark & Mortimer(57) **CLAIM**

The ornamental design for a mirror, substantially as shown and described.

DESCRIPTION

FIG. 1 is a bottom, right side, and front perspective view showing my new design;

FIG. 2 is a rear elevation view thereof;

FIG. 3 is a front elevation view thereof;

FIG. 4 is a left side elevation view thereof;

FIG. 5 is a right side elevation view thereof;

FIG. 6 is a top view thereof; and,

FIG. 7 is a bottom view thereof.

The convex surface portions, as viewed from the front of the mirror, have a contrasting appearance above and below the straight line dividing the convex portion.

1 Claim, 3 Drawing Sheets(56)
